UNITED STATES PATENT OFFICE.

EDWARD STORM, OF DETROIT, MICHIGAN.

FLOOR SUPPORT FOR CONCRETE SPOUTS.

Application filed August 15, 1924. Serial No. 732,255.

My invention relates to a new and useful improvement in a floor support for concrete spout, adapted for use in supporting a concrete spout which is used for distributing 5 concrete in constructing buildings formed from concrete.

In constructing buildings of concrete, it is customary to erect an elevating tower of sufficient height to permit the elevating of 10 the plastic material to a height which will permit the plastic material to flow downwardly by gravity through troughs to be distributed to the various portions of the building to which the concrete is desired. 15 These troughs are generally constructed in sections, the upper end of each adjacent section being positioned directly beneath the lower end of the upper preceding section so that the concrete or plastic material flowing from one section is deposited into the upper end of the next lower section. Owing to the great weight of the plastic material which is poured down these troughs, it is necessary that they be suitably supported, either by upright supporting standards, or by overhead cables, the overhead cable system being the one most 20 commonly used. The sections of the troughs which are approaching the position 25 at which the concrete is deposited in the forms arranged for it, do not permit of the overhead attachment to any great extent at their lower end, with the result that counterbalancing trusses are generally attached 30 to the upper end of the trough and weighted 35 at one end, the opposite end being held in engagement with the trough adjacent its lower end, so as to relieve the lower end of a portion of the downward pressure resulting 40 from the weight. This is particularly true of the last section of the chute, or trough, down which the concrete runs and is principally due to the fact that it is necessary to have the lower section pivoted, so 45 that it may be turned in various directions to distribute the concrete over a large area. The construction of the counterbalancing truss is an expensive arrangement and the assembly of it is difficult and involves much 50 labor. The weighting of the counterbalancing truss is also a difficult operation involving considerable expense owing to the labor used.

In the present invention, I have designed 55 a support for the lower section of the concrete chute or spout in which the concrete,

itself, is made to counterbalance the chute, so that the lower end of the trough, or chute, is relieved largely of the downward pressure. 60

It is an object of the present invention to provide such a section of a trough in which the use of a counterbalancing truss, or other assembly of weight, may be eliminated. 65

Another object of the invention is the provision of means for mounting the lower section of the trough, which will be simple in structure, and easy of operation and assembly. 70

Another object of the invention is the provision in connection with the lower trough, of such an arrangement of means for carrying the lower trough, which may be moved bodily and which will permit a 75 rotation of the trough freely about its upper end as a pivot, to afford a means of distributing the plastic material over a large area.

Other objects will appear hereinafter. 80

The invention consists in the combination and arrangement of parts hereinafter described and claimed.

The invention will be best understood from a reference to the accompanying 85 drawings which form a part of this specification and in which,

Fig. 1 is a side elevational view of the invention,

Fig. 2 is a section view taken on substantially line 2—2 of Fig. 1, 80

Fig. 3 is a sectional view taken on substantially line 3—3 of Fig. 2,

Fig. 4 is a sectional view taken on substantially line 4—4 of Fig. 1. 95

The invention, in its preferred form, comprises a platform, or base, 12, which is formed preferably square and which is provided with supports 13 for facilitating its movement from place to place. 100

The present structure is particularly adapted for laying floors and the like, and the base 12 is mounted upon a floor or other supporting surface. Projecting upwardly from the base 12 and secured thereto, at one end, is a post 14 which is mounted in the center of the base and braced to the corners of the base 12 by suitable braces 15. Mounted on the trough 16 is a block 17 having a pocket 18 formed therein, the upper end thereof being preferably semi-spherical. The upper end of the post is as shown in 110

Fig. 3 formed arcuate and the pocket 18 is of sufficient size to permit a movement of the block 17 on the post 14. Embracing the upper surface of the trough 15 are angularly turned bars 19, which have their ends 20 angularly turned and secured to the block 17 by any suitable fastening means. These members 20 project downwardly and are angularly turned at their ends and secured to angle irons 21 and 22 which are formed bow-shaped and pass at opposite sides of the post 14, as is clearly seen in Fig. 4. The ends of these members 22 and 21 are attached to the trough by rivets, bolts or other suitable securing means. Crossbars 23 and 24 are secured to the angle irons 21 and 22 by suitable bolts said angle irons 21 and 22 being provided with a plurality of openings, as shown in Fig. 4, for the projection of these securing bolts therethrough, so that the position of the bars 24 and 23 may be varied on the angle irons 21 and 22. It will be noted that the block 17 is mounted upon the trough 16 at approximately twice as great a distance from the lower end of the trough as from the upper end, two-thirds of the trough projecting downwardly from the block 17 and one-third of the trough projecting upwardly. The structure is such that the trough may be rocked upon the post 14, the clearance of the pocket 18 in the block 17 permitting this rocking movement. The cross bars 23 and 24 are arranged to limit the rocking movement, the adjustment of these bars 23 and 24 on the angle irons 21 and 22 determining the incline of the trough 16 relatively to the post 14. The members 19, being extended over the other side of the trough, will serve to prevent the trough being bowed upwardly at the point of support.

As the concrete is poured down the trough and passes to the lower end, a larger portion of the concrete is contained within the trough below the point of connection with the post than is contained within the trough above the point of connection with the post. The section of trough 16' which is above the upper end of the trough 16 and in communication therewith being also filled with concrete, or plastic material, is exerting a certain downward force. As the concrete in the portion of the trough 16 extending below the point of connection with the post 14 exerts a downward pressure through the angle irons 21 and 22, this downward thrust is delivered to the upper end of the trough, so as to relieve the trough 16 of a portion of its downward thrust, the structure being such that the downward thrust of the trough 16 below the point of connection with the post is counterbalanced by the downward thrust of the portion of the trough 16 which is above the point of con-

nection with the post 14. In this way the concrete itself is used to counterbalance and the presence of heavy counterbalancing weights is dispensed with, thus adding to the efficiency of the operation and reducing the cost of installing a concrete distributor of this class. It is apparent that the support is one which is positive and the structure such as may be made durable.

While I have illustrated and described the preferred form of structure, I do not wish to limit myself to the precise form of structure shown, but desire to avail myself of such variations and modifications as come within the scope of the appended claims.

Having thus described my invention, what I claim as new and desire to secure by Letters Patent is:

1. A trough support of the class described comprising a platform; a post projecting upwardly from said platform; a block adapted for mounting on a trough and provided with a pocket formed therein for the reception of the free end of said post, said pocket being of larger diameter than said post; brace members adapted to be secured to said trough at their opposite ends and projecting across and at opposite sides of said post; and means mounted on said brace members for engaging said post for limiting the rocking movement of said trough thereon.

2. A trough support of the class described comprising a supporting member; a post projecting upwardly from said supporting member; a block adapted for mounting on a trough, said block having a pocket formed therein for the reception of the free end of said post, said pocket being of larger diameter than said post; a brace member adapted to be secured at its opposite ends to said trough and passing in close proximity to one side of and across said post; and means mounted on said brace member for engaging said post for limiting the rocking movement of said trough relatively to said post.

3. A trough support of the class described comprising a supporting member; a post projecting upwardly from said supporting member; a block adapted for mounting on a trough to be supported, said block being adapted for engaging said post and for permitting the rocking movement of said trough relatively to said post; and brace members adapted to be mounted at each of their ends on said trough and projected on opposite sides of said post; cross bars mounted at opposite ends adjustably on said brace members on opposite sides of said post for connecting said brace members and for limiting the rocking movement of said trough relatively to said post.

4. A trough support of the class described comprising a supporting member; a post

projecting upwardly from said supporting member; a bearing member adapted to be mounted on said trough adapted for engaging the free end of said post for permitting 5 rocking movement of said trough relatively to said post; brace members projected on opposite sides of and across said post and adapted to be attached at their opposite ends to said trough; means associated with said 10 brace members for engaging the opposite sides of said post for limiting the longitudinal rocking of said trough; and means mounted on said brace members and projected over the upper surface of said trough 15 for resisting an upward thrust delivered to said trough at said point.

5. A trough support of the class described comprising a base; a supporting member projecting upwardly from said base; a bearing member adapted to be mounted on a trough to be supported and adapted for engaging the upper end of said supporting member for permitting the longitudinal rocking of said trough relatively to said 20 supporting member; a pair of braces adapted to be attached at their opposite ends to said trough adjacent its opposite ends, said braces being projected on opposite sides of said supporting member; and cross bars connecting 25 said braces for engaging said supporting member for limiting the longitudinal rocking of said trough, said cross bars being adjustably connected to said braces for regulating the degree of rocking of said 30 trough relatively to said supporting member and said braces preventing through engagement with said supporting member axial rocking of said trough.

6. A trough support of the class described

comprising a base; a supporting member 40 projecting upwardly therefrom; a block mounted on a trough to be supported intermediate its ends and adapted for engaging the upper end of said supporting member for permitting longitudinal rocking of said 45 trough relatively to said supporting member; a pair of braces adapted to be connected at their opposite ends to said trough adjacent its opposite ends and projected on opposite sides of said supporting member; 50 means mounted on said braces at opposite sides of said supporting member for engaging said supporting member for limiting the longitudinal rocking of said trough; and means mounted on said braces and adapted 55 to be projected over said trough for resisting the upward thrust delivered to said trough.

7. In a trough support of the class described comprising a base; a supporting 60 member projecting upwardly from said base; a bearing member adapted to be mounted on said trough and adapted for engaging said supporting member for permitting longitudinal rocking movement of said 65 trough relatively to said supporting member; a pair of braces adapted to be connected at their opposite ends to said trough adjacent its opposite ends; and means mounted on said braces for resisting upward thrust 70 delivered to said bearing member, said braces preventing, through engagement with said supporting member, axial rocking of said trough.

In testimony whereof I have signed the 75 foregoing specification.

EDWARD STORM.
